CLAIM

The ornamental design for a flat panel mounting adapter, as shown and described.

DESCRIPTION

FIG. 1 is a rear perspective view of a video light;

FIG. 2 is a rear elevation view thereof;

FIG. 3 is a front elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in FIGS. 1-7 illustrate portions that form no part of the claimed design.

1 Claim, 7 Drawing Sheets
